UNITED STATES PATENT OFFICE

2,662,972

APPARATUS FOR THE CONTROL OF ELECTRIC SWITCH LOCKS IN CENTRALIZED TRAFFIC CONTROL SYSTEMS FOR RAILROADS

George L. Trout, Painesville, Ohio, assignor to Westinghouse Air Brake Company, a corporation of Pennsylvania

Application June 29, 1949, Serial No. 102,074

9 Claims. (Cl. 246—161)

1

My invention relates to the control of electric switch locks for the protection of hand throw track switches in a centralized traffic control system for railroads.

In such systems, as applied to single track railroads, it is the practice to provide block signals for both directions which are controlled by continuous track circuits and are located in front of the track switches which connect the single track with passing tracks at the ends of the blocks and are for the protection of train movements over the switches and through the blocks which extend to other similarly equipped locations. The switches and signals are interlocked by means of approach locking relays, and a code type remote control system is provided having a station at each such location by means of which the switches and signals are manually controllable by code signals transmitted from a train director's office. An essential safety requirement for such systems is that an electric lock with approach or time locking protection must be provided for each outlying hand-throw switch which connects the main track with an industry track, blind siding or the like, at an intermediate point in a block.

My invention is particularly adapted for the control of electric locks for protecting the switches of such blind sidings in centralized traffic control territory.

A blind siding, as defined in the book, The Signal Dictionary, 1911 edition, is one having no station or open telegraph office. As applied to a centralized traffic control system, this term designates passing tracks equipped with hand throw switches at both ends and located within a single track block which extends between two adjacent stations of the system.

In conformity with the required practice for outlying hand throw track switches in centralized traffic control territory, the track switches of the blind siding to which my invention is applied are provided with electric locks with time locking protection, and control circuits are provided by which these may be released to permit train movements into or out of the side track only under proper traffic conditions and with the authorization of the train director, by the operation of a code controlled switch lock control relay at the station at one end of the block containing the blind siding. The circuits of my invention include the conventional provisions by which an unlock may be obtained for a train to enter the side track, when authorized, if the train is occupying a short release section directly in ad-

2

vance of the switch, or to leave the side track to enter the main track, provided the block is unoccupied and the signals which govern through train movements into the block are at stop and the usual approach locking relays associated with the signals are energized.

The principal object of the present invention is to provide additional facilities by means of which the train controller's authorization to enter the siding at either end initiates the operation of time locking apparatus for unlocking the switch at the other end of the siding after a suitable time interval. This feature of my invention provides facilities not heretofore available, for example, a train is enabled to enter the siding at one end, when authorized, leaving cars on the main track, and to then return to the main track over the switch at the opposite end of the siding to pick up these cars.

Another object of my invention is to more fully interlock the outlying track switches with the block signals than heretofore, by the provision of means whereby the authorization for unlocking the outlying track switch is governed independently of the condition of occupancy of the block by the condition of the approach locking relays associated with the block signals at both ends of the block. In accordance with this feature of my invention a train movement from the side track to the main track cannot be authorized when a signal has been cleared for a through train movement through the block nor immediately following the manual return of the signal to its stop position, but only after a suitable delay period imposed by the time locking apparatus associated with the signals.

My invention is not limited in its application to the particular case described by way of illustration, but is equally advantageous in other situations, such as for the protection of a single outlying track switch, for example.

One form of apparatus embodying my invention will now be described and the novel features thereof will then be pointed out in claims.

In the accompanying drawings Figs. 1A and 1B taken together show a track plan and the circuits for a typical single track block equipped with a conventional centralized traffic control system, which block includes a blind siding having the track switches 3W and 6W at its opposite ends protected by apparatus illustrating one embodiment of my invention.

In the drawings, similar reference characters refer to similar parts in both views, and to simplify the circuits, only the terminals for the local

sources of energy for the circuits are shown, these being designated B and N, respectively.

As shown in the drawings, the main track, illustrated schematically as a single line, is divided into track sections of suitable lengths by the usual insulated joints. Each track section is provided with a conventional track circuit identified by the reference character T with distinguishing numerical prefix. Each track circuit is provided with a track battery TB connected across the rails at one end for supplying energy to a track relay TR over the rails of its section.

The apparatus of my invention is suitable for use with signaling systems of various types, and by way of example is shown applied to a system of the controlled manual block type having no intermediate signals.

The operation of the track switches IW and IW at the ends of the block does not need to be considered in connection with my invention. It will be assumed that these switches remain in their normal position and that traffic movements through the block are governed by signals 2RA and 8LA, signals 2RB and 8LB remaining at stop. Signal 2RA is governed in a conventional manner in accordance with traffic conditions in the block by a polarized line relay 2RHD and a slow acting repeater relay 2RHP.

Relay 2RHD is controlled over a line circuit which includes the line wires 23 and 24 and extends the length of the stretch, and as will be clear from the drawing without tracing the circuit in detail, extends from terminal B at a front contact b of an approach locking relay 8LAS over front contacts of each of the track relays TR and front contact b of a switch lock relay WLR to terminal N at the contacts of a pole-changer relay 8RAPC associated with signal 8RA. Signal 2RA is of the color light type having lamps G, Y and R, the circuits of which are controlled by relay 2RHD and by a signal relay 2RAH. The latter relay is controlled in a conventional manner over a front contact of relay 2RHP, a back contact of the approach locking relay 2RAS, and a front contact of a signal control relay 2RHS, its circuit including a contact n which is closed only when the track switch IW is in its normal position as shown.

Normally the red lamp R of signal 2RA is lighted to cause signal 2RA to indicate stop, but when relays 2RHS and 2RHP are both energized, relay 2RAS releases to complete the circuit for relay 2RAH, which relay then becomes energized to cause signal 2RA to indicate caution or proceed by the lighting of lamp Y or G in place of lamp R. The caution indication of signal 2RA is displayed when relay 2RHD is energized in the reverse direction, as shown, and the proceed indication is displayed only when signal 8RA is cleared, in which case relay 8RAPC picks up to cause relay 2RHD to assume its normal position in which its left-hand polar contacts are closed.

Relay 2RAS is picked up in the usual manner when relay 2RHS is released, either over a back contact of the track relay 1TR when signal 2RA is put to stop by a train in section 1T, or after the usual time locking period imposed by a time element relay 2TER, when the signal is put manually to stop.

Signal 8LA, for the opposite direction, is governed over circuits by a signal relay 8LAH, its circuit being similar in all respects to those for signal 2RA. The line circuit for signal 8LA includes the line wires 21 and 22, and this signal is arranged to be cleared only when the track

switch IW is normal. The relays involved include the track relays, the switch lock relay WLR, the pole-changer relay 2LAPC for signal 2LA, the approach locking relay 2RAS, the polarized line relay 8LHD and its repeater 8LHP, the approach locking relay 8LAS, the time element relay 2TER and the signal control relay 8LHS.

The remote control system may be of the type shown in Letters Patent of the United States No. 2,229,249, issued January 21, 1941, to Lloyd V. Lewis for Remote Control Systems, to which patent reference may be made for a detailed explanation of those features of the centralized traffic control system not shown herein. For an understanding of my invention, it is sufficient to note that the system provides a plurality of intermittently available control channels between the office and the stations for the control of the block signals and of the adjacent track switches and also provides indication channels for indicating traffic conditions and the condition of the controlled devices at the office. Consideration of the manner in which this is accomplished is not needed, and to simplify the accompanying drawings, the channels employed for signal and switch lock control purposes have been replaced by the equivalent direct wire circuits. That is to say, as shown, the signal control relay 2RHS is controlled over the line wire 20 in accordance with the position of the corresponding signal lever 2SG at the office, and the signal control relay 8LHS and the switch lock control relay WLS are similarly controlled by the signal lever 8SG and switch lock lever WL at the office.

It is to be understood that the hand throw switches 3W and 5W at the ends of the blind siding are each provided with a suitable hand throw switch stand, such, for example, as is shown in Letters Patent of the United States No. 2,184,870, issued to H. L. Bone and K. G. J. McGowan on December 26, 1939, for Railway Switch Operating Mechanisms and that the switch operation is governed by a suitable electric lock having a lock magnet 3WL or 5WL, the circuits for which are arranged in accordance with my invention. The electric switch locks are preferably of the type shown in Letters Patent of the United States No. 1,126,834, issued February 2, 1915, to W. P. Neubert and W. E. Smith for Electric Switch Locks.

Considering for example the lock for switch 3W, in Fig. 1A, it will suffice to point out that the operating lever 8 of the switch stand is normally locked mechanically in a position to maintain the track switch locked normal by a lever latch attached to a segment 25 which is held in locking position by the bail 50 of a padlock. To unlock the switch the padlock must first be removed by the train crew to permit the segment 25 to be moved a short distance to a position to engage the locking dog 27 and to close contact 46 and to also open contacts such as 47 and 49 in the circuit for a normally energized indication relay, such as relay 5NWP. Then if traffic conditions as reflected by the circuits are such as to indicate that it is proper to unlock the switch, for example, if the train director has authorized a train which is occupying the short releasing section 03T to enter the siding by energizing the switch control relay WLS, the lock magnet 3WL will become energized to open contact 48 in the circuit for relay 5NWP and to lift the locking dog 27, permitting segment 25 to be moved to its full reverse position in which the switch operating lever 8 is free to be operated. The switch stand is equipped with the usual switch circuit controller and point

detector having normal and reverse contacts *n* and *r* in the circuit for relay 5NWP.

In accordance with my invention the switch indication relay 5NWP is made a polarized relay, and its circuit has a dual function. The circuit for relay 5NWP extends from terminals B and N at pole-changer contacts of the approach locking relay 2RAS at the left-hand end of the block over line wires to the location of switch 3W, thence over the contacts 47, 48 and 49, the normal contacts *n* of the circuit controller for switch 3W, line wires 26 and 28 and, the normal contacts *n* of the circuit controller for switch 5W, contacts 47a, 48a and 49a, a back contact *b* of a time element relay 5TER and thence through the winding of relay 5NWP.

The circuit for relay 5NWP is arranged in the usual manner so that the relay is short circuited by the contacts *r* when the switch is open or reversed, or by the switch lever contacts when these are in either the intermediate or the reverse position.

It will be understood that the closing of the neutral contacts *a* and *b* of relay 5NWP indicates that both switches 3W and 5W are properly locked in the normal position for through train movements, and that the polar contact *c* is closed to enable relay 5TER to be operated only when relay 2RAS is energized.

The time element relay 5TER has a timing contact *a* which closes only when energy is supplied to the relay for a time period which may be adjusted to have a duration of two minutes or more, and a checking contact *b* which is closed only when the relay is deenergized and contact *a* is in the position it normally occupies at the beginning of the measured time period. A suitable relay is shown for example in Letters Patent of the United States No. 1,936,965, issued July 17, 1934, to B. Lazich et al.

The circuit for the switch lock relay WLR by means of which the unlocking of the switches is authorized extends over contacts *a* and *b* of relay 5NWP at the location of switch 5W to the right-hand end of the block where the circuit is supplied with energy from terminals B and N over pole-changer contacts of the switch control relay WLS through the winding of an indicating relay WLP, and this circuit also serves two purposes, in that relays WLR and WLP are repeaters of relay 5NWP, with respect to the operation of their neutral contacts, while the polar contacts of relay WLR reflect the condition of the switch control relay WLS. The release of relay 5NWP releases relay WLP and thereby energizes an indication relay WK at the office, lighting a lamp WE to indicate the unlocked condition of the track switches.

In addition to the foregoing, the apparatus of my invention includes a stick relay 5AS at the location of switch 5W which is governed by relays WLR and 5TER and by two auxiliary line relays EAR and WAR. The purpose of relay 5AS is to enable switch 5A to be unlocked even though the release section 05T is not occupied, and to control the polarity of the current supplied over line wires 29 and 30 to a polarized repeater relay 5ASP at the location of switch 3W to enable that switch to be unlocked when section 03T is not occupied. Relay 5ASP is supplied with energy over contact *f* of relay WLR and therefore is energized only when an unlock is authorized.

Consideration of through train movements under the control of signals 2RA and 8LA is not needed for an understanding of my invention, ex-

cept to note that since relay WLR is a repeater of relay 5NWP, its front contacts *a* and *b* in the signal line circuits prevent the clearing of either signal except when the switches 3W and 5W are properly locked in their normal positions.

Assuming first that a train approaching switch 3W from the left occupies the release section 03T, and that the train crew by means of a telephone at the switch location has requested authority to enter the side track, the traffic director will reverse the switch lock lever WL, energizing the switch control relay WLS and thereby reverse the polarity of the current supplied to relay WLR, which relay assumes its reverse position, closing its right-hand polar contacts *d*, *e* and *f*, and in response to the closing of contact *f* of relay WLR, relay 5ASP becomes energized by current of reverse polarity, closing its neutral contact *a* and right-hand polar contact *c*.

Switch 3W may now be unlocked in the usual manner by moving the lock lever to complete the circuit for magnet 3WL which includes the neutral contact *a* and right-hand polar contact *c* of relay 5ASP, and back contact *e* of the track relay 03TR.

Alternatively, switch 5W may now be unlocked in the event the train is approaching from the right and is occupying the release section 05T, by moving the switch lock lever to complete the circuit for magnet 5WL which includes contacts *e* of relays WLR and 05TR.

A feature of my invention is that the reversal of relay WLR as above described also completes a circuit for the time element relay 5TER over the right-hand polar contact *e* of relay WLR, back contact *a* of relay 5AS, and the normal contact *c* of relay 5NWP. Relay 5TER thereupon becomes energized and immediately opens its contact *b* to release relay 5NWP, and after a time interval of two minutes, or more, closes its contact *a* to energize relay 5AS, which releases relay 5TER.

The opening of the lever contacts 47 and 49 or 47a and 49a by the train crew also opens the circuit for relay 5NWP, which relay upon releasing, releases relays WLR and WLP. When relay WLR is deenergized, its right-hand polar contacts *d*, *e* and *f* remain closed, but relay WLR opens its neutral contacts *a*, *b* and *c* in the signal line circuits, which insures that signals 2RA and 8LA are held at stop and prevents the energization of relays WAR and EAR, and relay WLP energizes relay WK to light the indication lamp WE at the office.

Since relay WLR is released by unlocking the switch or by the operation of relay 5TER, it follows that an unlock when accepted cannot be cancelled by the train director until the switch has been restored to normal and locked by the train crew nor can it be cancelled while relay 5TER is in operation.

The operation of this feature of my invention may be illustrated by assuming that the train which entered the side track via switch 5W after having restored and locked switch 5W normal arrives at switch 3W. When relay 5AS picks up at the end of the time period of operation of relay 5TER, its contacts *c* and *d* change the polarity of the current supplied to relay 5ASP from reverse to normal and relay 5ASP closes its left-hand contact *c* to prepare a circuit for magnet 3WL which does not include contact *e* of relay 03TR, enabling switch 3W to be unlocked to enable the train to re-enter the main track.

At the same time, a circuit for magnet 5WL is

prepared over contact *e* of relay WLR and contact *b* of relay 5AS, which does not include contact *e* of relay 05TR and consequently enables switch 5W to be unlocked if the train entered the side track via switch 3W and is to leave via switch 5W.

It will be seen from the foregoing that the effect of the operation of the switch lever WL is to prepare two circuits for unlocking each track switch to which my invention is applied, one to enable a train to leave the main track and another to enable a train to enter the main track with time locking protection, even though the block is occupied.

It follows that the system of my invention enables a train to obtain authorization to enter the side track over either switch, leaving cars on the main track, and to then return to the main track over either switch to pick up these cars. The necessity for the time delay imposed by relay 5TER will be seen from the fact that if cars are standing on the main track when the operator authorizes an unlock, the track circuit conditions are the same as when the block is occupied by a through train. In the latter case, relay 5TER provides the required time locking protection to prevent the unlocking of the switch in front of an approaching high speed train.

In the foregoing example the authorization to enter the block was granted before the train left the main track, in which case the block signals are held at stop by the train, but it may also be granted when the train is on the side track and the switches are closed and locked normal, even though the block is occupied, but under conditions affording time locking protection and then only if the block signals 2RA and 8LA are properly at stop.

A feature of my invention is the provision of a contact *d* of the approach locking relay 8LAS in the circuit for the switch lock control relay WLS. This prevents the operator from reversing relay WLR when signal 8LA is at clear, at which time relay 5NWP is energized to complete the circuit for relay WLR, and also for the time locking period by which the energization of relay 8LAS is delayed by the operation of relay 8TER, following the manual return of signal 8LA to stop. Another feature of my invention checks the condition of relay 2RAS and thereby provides corresponding protection with respect to signal 2RA, due to the fact that the circuit for relay 5NWP has been extended to the left-hand end of the block and pole-changer contacts of relay 2RAS included therein, as already explained, for controlling the position of contact *c* of relay 5NWP, in the circuit for relay 5TER.

It will be seen that even though relay WLR is reversed, relay 5TER will not operate if signal 2RA is at clear, nor during the period by which the energization of relay 2RAS is delayed by the operation of relay 2TER, following the manual return of signal 2RA to stop.

In addition, the energization of relays 5AS and 5ASP as is necessary to enable the switches to be unlocked to enter the block, is delayed by the time of operation of relay 5TER, providing time locking protection in the event the block is occupied by a through train.

Assuming next that a train standing on the side track has requested authorization to enter the main track at a time when the block is unoccupied, signals 2RA and 8LA are at stop and the approach locking relays 2RAS and 8LAS are both energized, as shown in the drawings.

Under these conditions the reversal of relay WLR by the operation of relay WLS causes the auxiliary line relay WAR to become energized over contacts *c* and *d* of relay WLR and the line wires 21 and 22, from the source at the location of signal 2RA. Relay WAR closes its contact *a* which causes the auxiliary line relay EAR to become energized over the other signal line circuit from the source at the location of signal 8LA. Relay 5AS picks up at once over contact *a* of relay EAR. Relay 5ASP is operated by relay 5AS from reverse to normal and closes its left-hand contact *c* which enables switch 3W to be unlocked, while the closing of contact *b* of relay 5AS enables switch 5W to be unlocked. The circuit for relay 5TER is opened at back contact *a* of relay 5AS and relay 5TER is not operated.

In the last example the condition of the block signals is checked by the fact that the signal circuits used include front contacts of the approach locking relays 2RAS and 8LAS. It will be seen that in accordance with my invention the condition of the signals is checked even though these circuits are open, due to the release of one or more of the track relays.

It will be seen that the objects of my invention are accomplished in an economical and practical manner with the use of a minimum number of line wires by efficient circuit design, each of the principal circuits having two or more distinct functions.

Although I have herein shown and described only one form of apparatus embodying my invention, it will be understood that various changes and modifications may be made therein within the scope of the appended claims without departing from the spirit and scope of my invention.

Having thus described my invention, what I claim is:

1. In combination with a stretch of single track railroad having block signals at its opposite ends for governing traffic movements through the stretch in accordance with traffic conditions therein, each signal having the usual approach locking relay associated therewith the energization of which indicates that such signal is at stop, said stretch including a hand throw switch equipped with an electric lock; a switch lock relay, a time element relay, and a stick relay, a circuit manually controllable from one end of the stretch only when the adjacent approach locking relay is energized for operating said switch lock relay, a circuit closed in response to the operation of said switch lock relay when the approach locking relay at the other end of the stretch is energized, for energizing said time element relay, a circuit closed by said time element relay when energized for a predetermined time interval for energizing said stick relay, and a circuit prepared by said stick relay when energized for enabling said electric lock to be energized to unlock said switch.

2. In combination with a stretch of single track railroad having block signals at its opposite ends for governing traffic movements through the stretch in accordance with traffic conditions therein, each signal having the usual approach locking relay associated therewith the energization of which indicates that such signal is at stop, said stretch including a hand throw switch equipped with an electric lock; a switch lock relay, a time element relay, and a stick relay, a circuit manually controllable from one end of the stretch only when the adjacent approach

locking relay is energized for operating said switch lock relay, a circuit closed in response to the operation of said switch lock relay when the approach locking relay at the other end of the stretch is energized, for energizing said time element relay, a circuit closed by said time element relay when energized for a predetermined time interval for energizing said stick relay, a track circuit in said stretch adjacent said switch having a normally energized track relay, and two circuits prepared by said switch lock relay when operated for enabling said electric lock to be energized to unlock said switch, one including a back contact of said track relay, and the other including a contact closed only when said stick relay is energized.

3. In combination with a stretch of single track railroad having block signals at its opposite ends for governing traffic movements through the stretch in accordance with traffic conditions therein, each signal having the usual approach locking relay associated therewith the energization of which indicates that the signal is at stop, said stretch including a blind siding having a hand throw switch at each end equipped with an electric lock; a switch lock relay, a time element relay, and a stick relay, all at the location of one of said switches, a circuit manually controllable from one end of the stretch only when the adjacent approach locking relay is energized for operating said switch lock relay, a circuit closed in response to the operation of said switch lock relay when the approach locking relay at the other end of the stretch is energized, for energizing said time element relay, a circuit closed by said time element relay when energized for a predetermined time interval for energizing said stick relay, a first track circuit in said stretch adjacent one of said switches, a second track circuit in said stretch adjacent the other switch, each having a normally energized track relay, a plurality of circuits prepared by said switch lock relay when operated for enabling said electric locks to be energized to unlock the switches at both ends of said siding, comprising one for each switch which includes a back contact of the adjacent track relay and one for each switch which is closed only when said stick relay is energized.

4. In combination with a stretch of single track railroad having block signals at its opposite ends for governing traffic movements through the stretch in accordance with traffic conditions therein, each signal having the usual approach locking relay associated therewith the energization of which indicates that such signal is at stop, said stretch including a hand throw switch equipped with an electric lock, a switch indication relay having neutral contacts and a polar contact, a switch lock relay, a time element relay, and a stick relay, means controlled by neutral contacts of said indication relay for preventing the clearing of either block signal except when said indication relay is energized, a circuit manually controllable from one end of the stretch only when the adjacent approach locking relay and said indication relay are both energized for operating said switch lock relay, a circuit for energizing said indication relay including contacts closed only when said switch is closed in its normal position and said electric lock is deenergized and in condition to prevent the unlocking of said switch, said circuit also including pole-changer contacts operated by the approach locking relay at the end of the stretch remote from that from which said switch lock relay is controlled, so

arranged that said indication relay closes its polar contact only when such approach locking relay is energized, a circuit for said time element relay including said polar contact and a contact closed by said switch lock relay when operated, a circuit closed by said time element relay when operated for a predetermined time interval for energizing said stick relay, and a circuit prepared by said stick relay when energized for enabling said electric lock to be energized to unlock said switch.

5. In a system for the control of an electric lock for an outlying track switch equipped with an electric lock and located in a stretch of railway track over which traffic movements are governed by block signals at its opposite ends, a switch control relay manually controllable from a remote point only when one of said block signals is at stop, a time element device, a track circuit in said stretch adjacent the track switch having a normally energized track relay, means controlled by the other block signal at stop and by said switch control relay when operated for initiating the operation of said time element device, and means controlled by said switch control relay when operated for preparing two circuits for enabling said electric lock to be energized to unlock the track switch, one of said circuits including a back contact of said track relay and the other including a contact closed in response to the operation of said time element device for a predetermined time interval.

6. In a system for the control of an electric lock for an outlying track switch equipped with an electric lock and located in a stretch of railway track over which traffic movements are governed by a block signal, an indication relay, an energizing circuit for said indication relay including contacts closed only when said switch is closed and locked in its normal position, an energizing circuit for said signal including front contacts of said indication relay, a switch lock relay manually controllable from a remote point only when said block signal is at stop and said indication relay is energized, a track circuit in said stretch adjacent the switch having a normally energized track relay, a time element device, and means controlled by said switch lock relay when operated for initiating the operation of said time element device and concurrently preparing two circuits for enabling said switch lock to be energized to unlock the track switch, one including a back contact of said track relay and the other including a contact closed by said time element device a predetermined time after its operation is initiated.

55 7. In a system for the control of an electric lock for an outlying track switch equipped with an electric lock and located in a stretch of railway track over which traffic movements are governed in two directions by block signals at opposite ends of the stretch, a track circuit in said stretch adjacent the track switch having a normally energized track relay, a switch control relay manually controllable from a remote point only when one of said block signals is at stop, a time element device, means for initiating the operation of said time element device in response to the operation of said switch control relay but only if the other block signal is at stop, and two circuits prepared by the operation of said switch control relay for energizing said electric lock to enable the switch to be unlocked, one of said circuits including a back contact of said track relay and the other including a contact closed in response to the operation of said time element device for a predetermined time interval.

11

8. In a system for the control of an electric lock for an outlying track switch equipped with an electric lock and located in a stretch of railway track over which traffic movements are governed in accordance with traffic conditions therein by manually controllable signals at opposite ends of the stretch, each signal having the usual approach locking relay which is energized only when the signal is at stop and has been at stop for a predetermined time interval following its manual return to stop, a track circuit in said stretch having a normally energized track relay, a switch control relay manually controllable from a remote point only when one of said approach locking relays is energized, a time element device, means for initiating the operation of said time element device in response to the operation of said switch control relay but only if the other approach locking relay is energized, two circuits prepared by the operation of said switch control relay for energizing said electric lock to enable the switch to be unlocked, the first including a back contact of said track relay and the second including a contact closed if said stretch is unoccupied and both approach locking relays are energized, and means controlled by said time element device effective when said stretch is occupied for closing said second circuit in response to its operation for a predetermined time interval.

9. In a system for the control of an electric lock for an outlying track switch equipped with
